DESIGN FOR A SHOE

Herman B. Delman, New York, N. Y.

Application January 18, 1939, Serial No. 82,405

Term of patent 3½ years

To all whom it may concern:

Be it known that Herman B. Delman, a citizen of the United States and resident of New York city, in the county of New York and State of New York, has invented a new, original, and ornamental Design for Shoes, of which the following is a specification, reference being had to the accompanying drawing, forming part thereof, in which—

Fig. 1 is a plan view of a shoe showing my new design; and Fig. 2 is a side perspective view thereof.

The design discloses a lateral opening thru the heel of the shoe, and a ribbon extending thru said opening, a part of which envelops the rear upper end of the heel and positioned to cover the heel of the user; and a part extends from said opening towards the toe and conceals a substantial portion of the shank.

I claim:

The ornamental design for a shoe, as shown and described.

HERMAN B. DELMAN.
